UNITED STATES PATENT OFFICE.

MILTON K. MARKMAN, OF CRYSTAL LAKE, ILLINOIS.

DESIGN FOR A SIGN SUPPORT.

Application filed December 15, 1926. Serial No. 20,059. Term of patent 14 years.

To all whom it may concern:

Be it known that MILTON K. MARKMAN, a citizen of the United States, and a resident of Crystal Lake, in the county of McHenry and State of Illinois, has invented a certain new, original, and ornamental Design for Sign Supports, of which the following is a specification, reference being had to the accompanying drawings, forming part hereof.

Fig. 1 is a front view of a sign support embodying a design forming the subject matter hereof;

Fig. 2 is a side elevation of the same.

What is claimed is:

The ornamental design for a sign support as shown.

MILTON K. MARKMAN.
